CLAIM

The ornamental design for a power supply cabinet, as shown and described.

DESCRIPTION

FIG. 1 is a front elevation view of a power supply cabinet in accordance with our new design;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof; and,

FIG. 7 is a top, front, and right perspective view thereof.

The broken lines in the drawings illustrate portions of the power supply cabinet which form no part of the claimed design.
